UNITED STATES PATENT OFFICE.

CHARLES A. KLINKNER, OF OAKLAND, CALIFORNIA.

INKING-PAD FOR HAND-STAMPS.

SPECIFICATION forming part of Letters Patent No. 326,042, dated September 8, 1885.

Application filed March 12, 1885. (No model.)

To all whom it may concern:

Be it known that I, CHARLES A. KLINKNER, a citizen of the United States, residing in the city of Oakland, Alameda county, State of California, have invented certain new and useful Improvements in Inking-Pads for Hand Printing-Stamps; and I do hereby declare that the following is a full, clear, and exact description of the same, reference being had to the drawings that accompany and form part of this specification, in which—

Figure 1 represents in isometric perspective a pad and its case or holder produced in accordance with my invention. Fig. 2 is a similar view of a pad without a protecting case. Fig. 3 illustrates in perspective the form and application of the fastenings by which the cloth is secured to the pad. Fig. 4 is a cross-section through the pad.

20 My invention relates to certain improvements in stretching and fixing surfaces of cloth and like suitable material upon the paste or body of inking matter or substance that is or may be used in the manufacture of pads 25 for hand printing stamps and blocks.

The improvement constituting my invention consists of fastening means of novel character, by the application and operation of which the cloth is so drawn and tightly held 30 around the edges over the pad that the tendency of the cloth to draw up and wrinkle after a time of use is overcome. The improvement contemplates also the ready removal of the cloth, to restretch it, or to renew the surface when too much worn.

35 My invention is particularly applicable to that form of inking-pad in which a body of inking or coloring matter contained in a suitable tray, pan, or shallow flat-bottom case is covered with cotton cloth or other fabric, whose porosity or openness of structure, permitting the inking matter to pass through under pressure of the stamp, forms a distributing-surface. The efficiency as well as the durability of the pad depends upon the smoothness and even character of this distributing-surface, for when wrinkling and working loose 45 the surface is no longer uniform in its action, an uneven distribution of the inking matter

takes place, and a consequent imperfect impression is obtained.

To confine and secure this surface in place I proceed to form a fastening for each edge or side of the piece of fabric by providing sufficient material on the fabric A to extend beyond the rim of the tray or case B, and then folding this edge portion down against the side and confining it by means of a clamping-strip, C, which I produce by bending up a strip of metal into the form shown in Fig. 3. 50

The top and bottom edges of a metal strip, C, are bent over and turned in toward each other, so as to fit tightly over the side or rim of the case or box, and particularly to press along the edges against the bottom of the box 55 and into the surface or top of the pad outside the rim.

A clamping-strip is provided for each side of the pad and each one in length corresponding to its side, so that when applied they 70 form a closely-fitting rim over the edges of the tray. In applying these strips, the material being smoothly stretched over the body of paste, its margin is turned down over the sharp edges of the pan or box, and the clamps 75 are sprung into place by first pressing the bent upper edge of each one down upon the cloth just inside the rim of the box, and then bringing the lower edge upward and under the bottom in such manner that the cloth is 80 caught and confined between it and the body of the box. This manner of securing the cloth is clearly shown in Fig. 2, and when all the edges are thus fixed the pad will have the appearance represented in Figs. 2 and 4. 85

To protect the inking-surface when not in use, the pad can be set into a case provided with a lid or cover, as shown in Fig. 1. In this complete form the pad is made to fit tightly into the box or holder D, so that the 90 clamps are held in place and cannot be loosened except by lifting out the pad.

The pan or box A and the clamping-strips are readily made from sheet-tin, and, except in the construction of the box portion, no solder, 95 cement, or fastening is required.

The cloth surface, while securely held at all points, can be loosened and restretched, or can

be taken off and renewed at any time without difficulty.

Having thus fully described my invention, what I claim, and desire to secure by Letters 5 Patent, is—

An inking-pad composed of the ink-receptacle B, a body or filling of absorbent ma-

terial, distributing-surface A, and clamps C C, constructed and combined substantially as described.

CHARLES A. KLINKNER. [L. S.]
